H. J. SIBLEY AND G. C. COIL,
FARE RECORDER,
APPLICATION FILED OCT. 20, 1919.

1,360,591.

Patented Nov. 30, 1920.

UNITED STATES PATENT OFFICE.

HARRY J. SIBLEY AND GROVER C. COIL, OF DAYTON, OHIO, ASSIGNEES TO OHMER
FARE REGISTER COMPANY, OF DAYTON, OHIO.

FARE-RECORDER.

1,360,591.

Specification of Letters Patent. Patented Nov. 30, 1920.

Application filed October 20, 1919. Serial No. 331,921.

To all whom it may concern:

Be it known that we, HARRY J. SIBLEY and GROVER C. COIL, citizens of the United States, residing at Dayton, in the county of Montgomery and State of Ohio, have invented certain new and useful Improvements in Fare-Recorders, of which the following is a specification.

This invention relates to certain new and useful improvements in zone fare recorders for recording fares according to the zone or distance traveled, and more particularly the invention relates to means whereby the printing mechanism and the recording or counter actuating mechanism cannot be operated at the same time, thus insuring a clear and accurate statement of fare collections and other data at all times. The present improvements are applied to a type of registering and recording machine such as is shown and described in Letters Patent No. 1,316,176, granted to John F. Ohmer, September 16, 1919, and comprise a locking device constructed and arranged so that the printing mechanism cannot be operated after the counter actuating mechanism has been started, and vice versa; the counter actuating mechanism cannot be operated when the printing mechanism is in any other than its home or normal position, all as will herein-after be more fully described in connection with the accompanying drawings. Referring in general terms to the said drawings, Figure 1 is a side elevation of a recording counter and printing mechanism to which the present improvements are applied, the upper portion of the mechanism such as the indicating devices etc. being omitted. Fig. 2 is a front elevation of the recording counter actuating member with which is also shown the present locking device, Fig. 3 is a top view of the lever which forms an element of the present improvements. Fig. 4 is a detached view of the locking lever, and Fig. 5 is a view of the combined unlocking and printing key.

In a more detailed or particular description of the present improvements, similar reference characters denote corresponding parts of the mechanism as illustrated in the said drawings.

Owing to the recording counter and the printing devices which coöperate therewith being fully disclosed in the prior patent to which reference has been made, it has been deemed unnecessary to illustrate more than

that which is necessary to disclose the present improvements in connection with the printing and counter actuating mechanisms.

The well known printing mechanism consists of two side plates —1— in which the ends or journals of a cam shaft —2— are mounted. The said cam shaft actuates the printing bar or platen —3— when the said shaft is rotated and thereby caused to engage the said platen and elevate it. One of the side plates —1— is shown in the drawings, the other being similar to it at the other side of the machine. On one end of the said shaft —2— a disk —4— is fixed which constitutes a feature of the printing device not involved in the present improvements. Also a one tooth gear —5— which is an element of the paper feeding device and constitutes no part of the present improvements, and a collar —6— which is a part of said one tooth gear and an element somewhat involved with the present improvements. The collar —6— has a recess —7— in the edge thereof in which a part of the unlocking and printing key —8— is insertable through an opening in a side of the machine casing; the lug —9— on said key enters the said recess —7— so that when the key is turned the cam shaft —2— will elevate the platen —3— and press the paper upon which the record is to be made, against the recording wheels or counter, all of which are well known and require no extended description. Until the key —8— is inserted the plunger head —10— lies in the recess in the said collar —6— and locks the cam shaft from rotation. Upon the insertion of the said key the tapered part of the lug —9— engages the head —10— and moves it out of the recess —7—. The head —10— has an extended stem —11— which is surrounded by a spring —12— which normally maintains the head —10— in said recess until the key is inserted. The stem and the spring referred to are mounted in a guide or housing —13— which is supported on the side plate —1—. The end of the stem —11— projects through the outer end of the housing and the projected end has fixed to it a head —14—. The head —14— engages the lower end of an upright lever —15— when the said stem is moved out by the insertion of the key. The lever —15— is of special construction and constitutes the main element of the present locking device. It is pivoted at —16— to the side of the frame. A tension spring —17—

has one end attached to the lever —15— below the pivot —16— and the other end secured to a convenient point of the side plate —1—. The position in which the said lever 5 is shown in Fig. 1 locks the counter actuating mechanism against operation after the key —8— is inserted. The insertion of the said key moves the stem —11— and therewith the head —14— which engages the end 10 of the lever —15— and the said lever is moved to the position shown in Fig. 1. When the said key is extracted for example after the printing operation is accomplished by the turning of the said key, the spring 15 —17— throws the said lever to the unlocking position, as shown by the broken lines and thus the counter actuating mechanism is unlocked. The lever —15— has a cam part —19— on the upper end thereof which 20 is adapted to transmit motion at right angles to a detent or locking lever —18—. The said cam part —19— enters the bifurcation —20— in the end of the said locking lever —18— and moves it in either direction 25 as shown in Fig. 2. The said locking lever is hung on a pivot —21— on a projection at the back of the machine frame above a plate 30 —30— to be again referred to. The slideable operating member —22— at the back of the machine is elevated and lowered by well known means in operating the recording counter —24—. Upright moldings —23— serve as guides for the said slideable operating member —22—, and the projections —25— thereon engage the pivotal pawl carrier —26— in the up and down movements of the said member —22—. The pawl carrier —26— carries a ratchet pawl —27— which engages the ratchet wheel —28— fixed 35 to the transmission wheel —29— said wheel —28— imparting movement to the recording wheel —24—, all of which is of well known construction and operation. The slideable operating member —22— has fixed 40 to it the plate —30— hereinbefore referred to in connection with the locking pawl or lever —18—. It will therefore be seen that the plate is a fixed part of the member —22— and moves therewith. The said plate 45 moves in the path of the lever —18— and when said lever —18— is moved to the position above said plate as is shown in Fig. 2, it acts as a stop and prevents the operating member —22— being elevated. This condition takes place when the unlocking and printing key —8— is inserted to operate the printing devices. When the said key is withdrawn as before stated, the cam end 50 —19— of the lever —15— moves the lever —18— from above the plate —30—. This is accomplished through the action of the spring —17—.

It is important in machines of this character that neither mechanism to wit, the 55 printing mechanism or the recorder mecha-

nism be interfered with during the performance of their respective functions, by an attempt to operate both concurrently. In the drawings and the description in connection therewith a simple and effective 70 means is shown for accomplishing this object. We do not, however, wish to be limited to the particular means thus shown, and described for it will be apparent to those skilled in the art that some changes and 75 modifications may be made therein to bring about the same result without departing from the spirit of the invention as claimed.

Having described our invention, we 80 claim:—

1. The combination with the actuating mechanism of a fare recorder, and the printing mechanism thereof, of a bifurcated detent adapted to lock said actuating mechanism against operation, a lever engaging the bifurcation of said detent to move it in and out of a locking position, a head engaged by said lever, said lever being adapted to actuate said head to lock the printing mechanism against operation when the detent is moved to its unlocking position relatively to the said actuating mechanism.

2. The combination with the actuating mechanism of a fare recorder, and the printing mechanism thereof, including a key for unlocking and actuating said printing mechanism, of a bifurcated detent adapted to be moved to positions to lock and unlock said actuating mechanism, a lever having a cam portion engaging the bifurcation of said detent, a bolt having an actuating engagement with said lever and a locking engagement with an element of the printing mechanism respectively, said bolt being operated to unlock the printing mechanism by said key, and to actuate the said lever.

3. The combination with the actuating mechanism of a fare recorder, and the printing mechanism thereof, including an insertible printer operating key, of a bifurcated detent adapted to be moved in and out of the path of said actuating mechanism, a lever having a cam portion which enters the bifurcation of said detent and moves said detent to either position, a bolt adapted to lock and unlock the printing mechanism and to simultaneously actuate said lever when moved by said key to a position to unlock the printing mechanism whereby the said detent is moved to a position to lock the recorder actuating mechanism, and a spring adapted to return said lever to the position to unlock the said recorder actuating mechanism when the said key is extracted.

In testimony whereof we affix our signatures.

HARRY J. SIBLEY.
GROVER C. COIL.
